COMPOSER PRINTING MACHINE

William C. Huebner, Chicago, Ill.

Application September 19, 1932
Serial No. 633,729

7 Claims. (Cl. 95—73)

This invention relates to improvements in composer printing machines, and more particularly photographic printing machines commonly called photo composers.

5 In photographic printing machines for producing press plates and the like for ultimate use in printing presses, the press plate or other print receiving element is generally held stationary and the print producing element is generally so mounted as to move in a plane parallel to the print receiving element and in such manner that it may move to any desired predetermined location with respect to the print receiving element. The press plates sometimes require only one 15 large image impression as in the case of window displays; sometimes require a multiplicity of repeated small images, as in the case of stamps or labels; and sometimes require a combination of different size images in order to utilize the entire 20 available printing surface.

Heretofore, in photographic printing machines or composers of the type indicated, the negative or other image producing or printing element suitably mounted in a negative frame or holder, 25 has been attached to a sub-carriage, which sub-carriage in turn has been mounted on a main carriage with adjusting and operating mechanisms so arranged that the main carriage is movable back and forth in one direction and the sub- 30 carriage movable back and forth on the main carriage in a direction at right angles to the movement of the main carriage whereby to allow of positioning the center of the print producing element at any desired point with reference 35 to the print receiving element or press plate. Such prior machines have been very heavy and cumbersome; require a great deal of accurate machining to allow for the lines of movement of the carriage and sub-carriage respectively; in- 40 volve a large number of operating parts for the carriage and sub-carriage respectively, with the result that the same have been unduly expensive, thus militating against their wide use and, furthermore, because of the number of relatively 45 moving parts, it has been extremely difficult to obtain the necessary extreme accuracy in the positioning of the image producing element, particularly as required in the case of a series of press plates for multi-color printing.

50 One object of the present invention is to provide a composer printing machine which is comprised of the minimum number of essential parts; which is of materially lesser weight than those heretofore employed for work of given size; which 55 is much cheaper to manufacture because of the

fewer number of parts and lesser amount of accurate machining than in the case of prior machines for similar purpose; and which is so constructed as to minimize possibilities of mis-register or inaccuracies in operation when operated 60 by the ordinary operator.

More specifically, an object of the invention is to provide a composer printing machine wherein in the printing element such as a negative is mounted on a single beam or monorail or single 65 carriage, which beam, monorail or carriage, with the print producing element attached thereto in relatively fixed position, is itself adjustable in two directions at right angles to each other in a plane parallel to the print receiving surface, 70 whereby to minimize the chances of mis-register when locating the print-producing element with reference to the print receiving element.

Other objects of the invention will more clearly appear from the description and claims here- 75 inafter following.

In the drawings forming a part of this specification, Figure 1 is a front elevational view of a machine embodying the improvements. Figure 2 is an end elevational view of the machine shown 80 in Figure 1, the elevation being of the right hand end of the machine as illustrated in Figure 1. Figure 3 is an enlarged vertical, sectional view corresponding to the line 3—3 of Figure 1. Figure 4 is an enlarged horizontal, sectional view 85 corresponding to the broken line 4—4 of Figure 5. Figure 5 is a vertical, sectional view corresponding to the line 5—5 of Figure 4, parts being broken out to better accommodate the view on the sheet. And Figure 6 is an end elevational 90 view of a machine embodying the improvements showing the same, adjustable for use in either vertical, horizontal or in intermediate position.

Referring first to the structure illustrated in Figures 1 to 5, inclusive, the machine is shown 95 as embodying a suitable heavy pedestal or base 10, preferably in the form of a hollow casting, the same having integrally formed therewith, an upper table or horizontal bed 11 extending laterally to each side for a distance correspond- 100 ing to the particular size of machine to be built. Carried by the base casting is a vertically ar- ranged frame consisting of two side hollow and preferably built up rectangular columns 12—12, each suitably secured at its lower end to the ends 105 of the table section 11. The columns 12 are rig- idly united and maintained in proper spaced and parallel relation by a top cross brace 13 also preferably in the form of a hollow rectangular casting suitably flanged at its ends, as indicated 110

at 113, and bolted to the respective columns as shown at 14—14. In this manner a hollow rectangular frame in vertical position is provided of sufficient size to allow of the necessary movements of the negative holder and beam herein-after described.

The table section 11 is provided with a preferably machined top, horizontal, flat surface 15 on which is slidably mounted, inwardly and outwardly, a supporting frame for the backing of the usual press plate or other print-receiving element on which the images are to be reproduced. Said supporting frame comprises a bottom bar 16 slidably mounted on the surface 15 and two upright bars 17—17 laterally spaced and all rigidly united. The upright bars 17 are inwardly offset with reference to the forward edge of the bottom bar 16 so as to provide a ledge or shelf 18 on which rests the lower edge of the backing support for the press plate which preferably is in the form of a rectangular heavy slate 19 with a flat front surface extending vertically and to which the press plate 20 may be secured in desired position by any suitable means, as for instance, vacuum, but the details of which are not deemed necessary of illustration or specific description. The slate backing 19 is secured in place by any suitable means such as the bolts 21—21 extended through the upright bars 17 and alined openings in the slate, the nuts of the bolts 21 being flush or countersunk within the surface of the slate so as to avoid any projections on the slate surface.

In the particular embodiment illustrated, to obtain the necessary clearance between the print-receiving and print-producing element when making a relative shift therebetween, the press plate support is made adjustable inwardly and outwardly relative to the print-producing element hereinafter described. To effect these clearance movements of the press plate, the support for the slate backing is formed with rearwardly extended upper and lower racks 22—22 slidably supported on the upper surface of the cross-beam 13 and table surface 15, respectively, said racks 22 being four in number and preferably in alinement with the upright bars 17. Extending transversely of the machine and suitably journaled in bearing castings 23 secured to the columns, are upper and lower shafts 24 and 25, each of which carries pinions 26—26 meshing with the respective racks 22—22. Also secured to each of the shafts 24 and 25 near their right hand ends, as viewed in Figures 1 and 4, are pinions 27—27 meshing with upper and lower racks on a vertically movable operating bar 28, as best shown in Figure 5. Said bar 28 is suitably guided in the upper cross beam 13 and by backing roller 29 at its bottom end, said bar 28 being extended through the table 15 and having pivotally connected thereto a link 30 which in turn is pivotally connected to an operating lever 31 suitably supported on the base casting 10, said lever 31 having a handle 32. In Figure 5 the press plate support is shown in its outermost or operative position adapted to have the press plate thereon placed in pressure contact with the print-producing element. By lifting the operating lever 31, it is apparent that the shafts 24 and 25 will be rotated counter clockwise, thus retracting the press plate support and provide for the necessary clearance when making shifts. Conversely when the print-producing element has been adjusted to the desired position preparatory to an exposure, the lever 31 is depressed and the press plate

and support brought back to operative position again.

As best shown in Figure 4, each column 12 has the front plate 112 thereof preferably laterally extended at each side of the column so as to provide guides for what may be termed cross heads 33, one on each column and adapted for up and down movement with respect to the columns of the frame.

To effect simultaneous and equal vertical adjustments of the cross heads 33, the following arrangement is employed. Secured to the front plate 112 of each side column and within the respective cross heads, is a stationary or fixed rack 34 having its teeth facing toward the front of the machine, and another locking rack 35 having its teeth facing laterally outwardly, and each rack 35 being adjustable within a limited range with respect to the supporting column. Suitably journaled in the lower ends of the cross heads is a transversely extending shaft 36 carrying, adjacent each end thereof, a pinion 37 co-operating with the fixed racks 34. At the operating end of the machine, the right hand end as shown in Figure 1, said shaft 36 is extended and provided with a clutch member 38 with which is adapted to co-operate a corresponding clutch element 138 carried by an operating crank arm 39 loosely rotatably and slidably mounted on the end of the shaft 36. As will be evident, by engaging the clutch members 38 and 138 and by rotating the crank arm 39, the two cross heads may be given their major or coarse adjustments vertically upwardly and downwardly by reason of the co-operation of the pinions 37 and racks 34 and, in actual practice, these major adjustments will be made to the nearest inch called for by the lay-out sheet, it being understood that suitable scales 40 will be employed on the machine for this purpose.

The minor or micrometer adjustments of the cross heads vertically to the thousandth part of an inch as required in actual practice, is effected through the following means, particular reference being had to Figures 1 and 3. Each rack 35, at its upper end, is provided with a threaded laterally extended nut 41 with which co-operates a threaded stem 42 of a screw swiveled in a fixed bracket 43 carried by the upper end of the corresponding column so that, as the screw 42 is rotated, the same is prevented from vertical movement but will impart a fine or micrometer adjustment vertically up and down for the corresponding rack 35. Each said screw preferably carries, at its upper end, a knob 44 having a micrometer scale 45 thereon so co-ordinated with the threads 42 that each mark on the scale 45 indicates one thousandth of an inch adjustment of the rack 35. Each adjusting screw has secured thereto a worm gear 46, the same meshing with worms 47 carried by another transversely extending shaft 48 suitably mounted in the brackets 43 at the tops of the columns. The shaft 48 is provided with a clutch and crank handle arrangement 49, 50 corresponding to that described for the shaft 36 so that, upon rotation of the shaft 48, the simultaneous adjustment is effected equally for the cross heads at each side of the machine.

After the major and minor or coarse and fine adjustments of the cross heads have been made, the cross heads are then locked in their desired adjusted position by means of another operating shaft 51 extending transversely of the machine and suitably journaled at its ends in the cross

heads, said shaft 51 carrying at each end thereof a segmental cam 52 co-acting with a locking block 53 carried by the respective cross heads, said locking blocks 53 being horizontally movable inwardly and outwardly upon rotation of the cams 52 and, when forced inwardly having the teeth at the inner ends of the blocks thereof engaged with the teeth of the racks 35, respectively, and thus locking the cross heads in the desired vertically adjusted position. As shown in Figure 1, the shaft 51 is provided with a suitable operating handle 54 at its right hand end for the purpose of turning it and the cams carried thereby.

15 Horizontally, slidably supported in the two cross heads 33 near the tops thereof is a relatively heavy monorail, beam or unitary supporting member 55, the same being retained by suitable overhanging guide plates 56-56. Said beam or monorail is preferably of vertical, elongated, rectangular cross section as best shown in Figure 5 so as to minimize any tendency to sag when carrying the negative holder or other print-producing member. At its center, the beam or monorail, on the inner side thereof is preferably provided with a shelf casting 57 having an upper horizontal ledge or support for temporarily supporting the negative holding frame 58 when the latter is being put in place. The holder 58, which

20 may be of any suitable character for retaining a glass negative or positive, flexible film or other print-producing element proper, is located and positioned on the monorail by any suitable registering means for that purpose, such as well known in the art and preferably by means of dowel pins 59 fixed to the inner side of the monorail and adapted to co-operate with corresponding dowel holes in the holder frame 58. When in place, the holder frame is retained by

25 suitable means such as the screws 90.

The negative is shown in the drawings as having two register lines inscribed thereon and intersecting at 91. In actual practice these lines will not be actually inscribed on the negative but are shown to illustrate the center point which will always be located at a predetermined distance above the monorail, which distance will accord with the different sizes of negative holders employed. The vertical scale indicator will be set

30 to accord with the size holders employed, which is deemed unnecessary of illustration herein.

The adjustments of the beam or monorail horizontally, that is at right angles to the vertical adjustments thereof, effected as hereinbefore described, are accomplished as follows: Secured to the outer face of the monorail is a fixed or rigid rack 60 with its teeth facing upwardly and another rack 61 with its teeth facing downwardly, the rack 61 being adjustable for a limited distance horizontally with reference to the monorail proper. The major or coarse adjustments of the monorail or beam horizontally are made by a pinion 62 which engages with the rack 60, said pinion 62 being carried at the inner end of a short shaft 63 suitably journaled in the cross head and extending to the front of the machine and adapted to be rotated by another clutch and crank arm arrangement 64, 65. The minor or micrometer adjustments are effected as follows, particular reference being had to Figures 1 and 4. The beam 55 at its right hand end is provided with a threaded nut section 66 in which is threaded a micrometer screw 67 similar to the one previously described, the inner end of the stem of the screw having a swiveled connection 68 with a lug

formed integral with the outer or right hand end of the movable rack 61. As will be evident, upon rotation of the micrometer screw 67, the adjustments to thousandths of an inch between the rack 61 and beam 55 proper may be effected and thereupon the beam or monorail is locked in its adjusted position horizontally as follows: Vertically slidably mounted in the right hand cross head 33 is a toothed locking block 69 having a rack 70 at its lower end with which co-operates a segmental gear 71 carried by a horizontally extending short shaft 72 provided with an operating handle 73, the said shaft 72 being suitably journaled in the cross head, as clear from Figures 1 and 3. In Figure 3, the locking block 69 is shown in locked position and, obviously, by swinging the lever 73 upward or clockwise, the block will be disengaged, thus releasing the monorail for adjustment.

From the preceding description, it will be seen that the negative or other print-producing element employed in this general class of machine, is attached to the monorail or beam and retains a relatively fixed position with respect thereto during all adjustments. The one monorail or beam is itself adjustable in the two directions at right angles to each other in a plane parallel to the print-receiving surface, thus eliminating the sub-carriages heretofore deemed necessary and hence greatly reducing the number of parts and cost of manufacture; eliminating many of the sources of possible inaccuracies of adjustment and misregister inherent in prior types of machines employing said sub-carriages; and also greatly simplifying the operation of the machine since the operating parts for effecting the necessary adjustments are reduced to the minimum and compactly located at one side of the machine.

In the machine shown and described, the necessary clearance movements between the print-receiving and print-producing elements are effected by moving the print-receiving element inwardly and outwardly, but, as will be understood by those skilled in the art, the necessary clearance movements might be equally well effected by having the print-receiving element always maintained in fixed position and the clearance movements imparted to the negative holder inwardly and outwardly relative to the monorail, without departing from the spirit of the invention.

Referring to Figure 6, the arrangement of supporting frame, cross heads, monorail, press plate support and operating means for the various parts is the same as that hereinbefore described for Figures 1 to 5. In Figure 6, however, the main frame designated generally by the reference character A is provided with a suitable heavy pivot lug 70 on its under side, which in turn is pivotally connected through the heavy pivot 71 with the base casting 110 whereby the machine may be utilized as either a vertical type, horizontal type, or any intermediate inclined type machine without in any wise departing from the spirit of the invention, thus adapting the machine to meet the preferences of different operators.

Referring back to Figure 2, a horizontal rail 72 carried by brackets 73 secured to the respective cross heads is illustrated in dotted lines, said rail 72 indicating conventionally a suitable type of support for an arc lamp generally utilized in machines of this character, it being understood that the arc lamp will be positioned in front of the negative when exposure is made. It will also be understood that various other refinements may

be employed such as counterweights for the movable parts; various pointers co-operating with the main and micrometer scales, but since these form no part of the invention, illustration thereof is deemed unnecessary. Likewise it is deemed unnecessary to illustrate the means by which pressure contact is obtained between the print-producing and print-receiving elements at time of exposure, since such means may be of any desired type, although the vacuum type is preferred.

The construction herein illustrated is the one now deemed preferable but the same is merely illustrative and not by way of limitation. All changes and modifications are contemplated that come within the scope of the claims appended hereto.

What is claimed is:

1. In a machine of the character described, the combination with a base; of means for supporting a print-receiving element in position; a supporting member adapted to have a print-producing element attached thereto and retained in a relatively fixed relation with respect to said member; and means for adjusting said member with a print-producing element in fixed relation thereto, in two directions at right angles to each other in a plane parallel to the print-receiving element.

2. In a machine of the character described, the combination with a frame; of a support for a print-receiving element; a monorail to which a print-producing element is adapted to be attached; means for adjusting said monorail back and forth in one line relative to the frame; and means for adjusting said monorail back and forth in another line at right angles to said first line of movement whereby, the print-producing element may be positioned at any desired point relative to the print-receiving element by adjustment of said monorail only.

3. In a machine of the character described, the combination with a vertically disposed frame; of means for supporting a print-receiving element in vertical position; a monorail to which a print-producing element is adapted to be attached in vertical position parallel to the print-receiving element; means for adjusting said monorail on said frame vertically and in a vertical plane parallel to the print-receiving element; and means for adjusting said monorail horizontally relative to said frame and print-receiving element and in a plane parallel to the latter.

4. In a machine of the character described, the combination with a horizontally disposed frame; of means for supporting a print-receiving element in a horizontal position; a monorail to which a print-producing element is adapted to be attached and positioned horizontally over the print-receiving element; means for adjusting said monorail back and forth in one direction in a horizontal plane; and means for adjusting said monorail back and forth in a direction at right angles to said first named direction and also in a horizontal plane parallel to the print-receiving element.

65

5. In a machine of the character described; the combination with a base; of a frame adjustably mounted on said base and adapted to assume vertical, horizontal or intermediate position; means mounted on said frame for supporting a press plate in a plane parallel to said frame; a monorail adapted to have a print-producing element attached thereto in position parallel to the press plate; and means for adjusting said monorail relative to said frame in two directions at right angles to each other and in a plane parallel to the press plate.

6. In a machine of the character described, the combination with a base; of a frame thereon; supporting means for a press plate; a unitary beam for support and attachment thereto of a print-producing element in operative position relative to the press plate; laterally spaced cross heads mounted on said frame to move in one direction and by which said beam is carried and adapted for corresponding movement relative to the press plate, in a plane parallel thereto, said beam being also slidably mounted in said cross heads to move in a direction at right angles to said first named direction; means for adjusting and locking in adjusted positions, said cross heads relative to the frame and the beam relative to the cross heads; and means for effecting a relative movement toward and from each other of the press plate and print-producing element when the same are mounted on their respective supports.

7. In a machine of the character described, the combination with a base; of a frame thereon; supporting means for a press plate; a unitary beam for support and attachment thereto of a print-producing element in operative position relative to the press plate; laterally spaced cross heads mounted on said frame to move in one direction and by which said beam is carried and adapted for corresponding movement relative to the press plate, in a plane parallel thereto, said beam being also slidably mounted in said cross heads to move in a direction at right angles to said first named direction; means for effecting major adjustments of said cross heads simultaneously on the frame; supplemental means for effecting additional minor adjustments in the same direction, relatively between the beam and cross heads; means for effecting major adjustment of the beam relative to the cross heads in a direction at right angles to the cross head adjustments on the frame; supplemental means for effecting additional minor adjustments of the beam relative to the cross heads in a direction at right angles to the cross head adjustments on the frame; and means for effecting relative movement toward and from each other of the press plate and print-producing element when mounted on their respective supports.
